UNITED STATES PATENT OFFICE.

CHARLES C. GRIDLEY, OF COLUMBUS, OHIO.

SAD-IRON.

1,196,677.

Specification of Letters Patent. Patented Aug. 29, 1916.

Application filed August 24, 1915. Serial No. 47,081.

To all whom it may concern:

Be it known that I, CHARLES C. GRIDLEY, a citizen of the United States, residing at Columbus, in the county of Franklin and State of Ohio, have invented a new and useful Sad-Iron, of which the following is a specification.

The device forming the subject matter of this application is a sad iron, and one object of the invention is to provide a structure of this sort which, at its toe, is so constructed as to retain heat, novel means being provided for directing the flame from a burner against the toe.

Another object of the invention is to provide novel means whereby the flame spreader is made effective as a means for holding the burner in position.

Another object of the invention is to provide novel means for assembling the flame spreader, the hand shield and the handle with the top of the iron.

It is within the province of the disclosure to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawing: Figure 1 shows in longitudinal section, a sad iron embodying the present invention, parts being broken away; Fig. 2 is a cross section on the line 2—2 of Fig. 1; Fig. 3 is a rear elevation of the iron, parts being omitted; Fig. 4 is a bottom plan of the lid of the iron and parts carried thereby; Fig. 5 is a fragmental view wherein is disclosed the hinged connection between the lid of the iron and the body portion thereof; Fig. 6 is a fragmental top plan showing the forward portion of the lid, the view depicting the means whereby the lid is held in a closed position; Fig. 7 is a fragmental top plan showing the toe portion of the body of the iron.

In carrying out the present invention there is provided a body 1 including a bot-

tom 2 and side walls 3 which converge to a point at the front of the iron to define an upright edge which is rearwardly concaved as shown at 4 to form a reduced, 60 forwardly presented toe 5 adapted to enter ruffles, plaits and the like during the ironing operation. Where the side walls 3 converge at the front end of the iron there is formed a thickened, upright standard 6. 65 This standard 6 contains a considerable quantity of metal, adapted to retain heat at the toe of the iron. In its interior, the body 1 of the iron is provided with a plurality of transverse fins 7, acting at once, 70 as reinforcements and as heat retaining elements. The rear end of the body 1 is open, but the rear portions of the side wall 3 are thickened to form reinforcing lugs 8 from which extend rearwardly, ears 9. Projecting toward each other from the inner faces of the ears 9 are spindles 10 flattened on one side as shown at 11. Projecting upwardly from the standard portion 6 is a reduced boss 12 in the rear edge of which 80 is formed a notch 14.

The invention comprises a lid 15 equipped near its rear end with a transverse, depending wing 16 having forward extensions 17. Ears 18 project rearwardly from the wing 85 16 and are provided in their rear edges with notches 19 opening into circular seats 20. The spindles 10 on the body portion 1 of the iron are received in the seats 20 and thus a hinged union between the body and the 90 lid 15 is formed, whereby the lid may be opened. Owing to the fact that the spindles 10 are flattened on one side as shown at 11, the spindles may be inserted into the seats 20 through the notches 19 when the lid 15 95 is in a position midway between a fully opened position and a fully closed position. When, however, the lid is fully opened or fully closed, the lid cannot be detached from the spindles. The forward end of the lid 100 15 is provided with a notch 21 through which the boss 12 on the body 1 is adapted to pass, when the lid is swung downwardly to a closed position. The lid 15 carries a pivot element 22 on which is mounted for 105 swinging movement a latch 23 having a handle 24. The latch 23 is adapted to be engaged in the notch 14 of the boss 12 to hold the lid 15 closed. However, the handle 24 may be swung around until it engages a stop 110 25 on the lid 15, under which circumstances, a notch 49 in the latch 23 will coincide with

the notch 14 in the boss 12, whereupon the lid 15 may be swung to an open position. Adjacent its forward end, the lid 15 is equipped with a depending bracket 26 having a notch 27 in its lower extremity.

5 The invention comprises a burner tube 28 lying in a notch 29 formed in the wing 16 of the lid 15 and adapted to be received in a notch 30 formed in a boss 31 upstanding from the bottom 2 of the body 1 of the iron. 10 The burner tube 28 is provided with a plurality of transverse combustion orifices 35, the rear end of the burner tube being upwardly extended and being provided with 15 a plurality of air inlets 32. The upwardly extended rear end of the burner tube carries a controlling valve 33 and terminates in a rearwardly extended, elevated extension 34 adapted to receive a gas tube or pipe (not 20 shown). Owing to the specific disposition of the upwardly inclined rear end of the burner tube 28 and its extension 34, these parts will lie in an out-of-the-way position, beneath the arm of the operator. The up- 25 per, forward end 36 of the burner tube 28 is downwardly inclined so as to direct the flame through an opening 37 formed in the forward end of the burner tube. Through this opening, the flame is directed against 30 the thickened standard 6 and this portion of the iron, consequently, is always maintained in a highly heated condition. The forward end of the burner tube 28 terminates in an upright extension 38 which abuts 35 against the rear face of the bracket 26 on the lid 15.

Disposed below the lid 15 and above the burner tube 28 is a flame spreader 39 having perforations 40. The rear end of the 40 flame spreader 39 abuts against the extensions 17 of the wing 16. The flame spreader 39 comprises a downwardly and forwardly extended toe 41 which passes through the extension 38 of the burner tube 28 and enters the notch 27 in the lower end of the bracket 26, on the top 15. The flame spreader, therefore, constitutes a means whereby the burner tube 28 is held in place upon the top 15, the burner tube being rigid 45 so that it is held securely in the notch 29 on the wing 16 on the lid 15. The flame spreader 39 is equipped with upstanding projections 42 which bear against the under face of the lid 15. The lid, in its turn, is supplied with upstanding projections 43 on which rests a shield 44, the under surface of which is provided with an asbestos lining 45. The shield 44 is curved transversely and serves both to protect the hand of the 50 user and to maintain cool a handle 47 carried by a frame 46 which is superposed upon the shield 44. The handle 47 slants downwardly and rearwardly, and consequently, the pressure is transmitted into the heel 55 portion of the iron as distinguished from

the toe portion thereof. Securing elements which may be bolts 48 pass downwardly through the bottom portion of the frame 46, through the projection 43 and the lid 15, and through the projection 42 on the flame 70 spreader 39, the flame spreader thus being held to the lid.

The operation of the structure will be understood by those skilled in the art, but especial attention is directed to the following features. It is to be observed that the toe portion of the iron comprises a thickened standard 6 against which the flame is directed through the opening 37 at the forward end of the burner tube 28. The flame 80 spreader 39 through the instrumentality of its projection 41, serves to hold the burner tube 28 in place. In view of the foregoing, the securing elements 48 serve to hold in place the handle supporting frame 46, the 85 shield 44, the flame spreader 39 and the burner tube 28.

Having thus described the invention, what is claimed is:—

1. A sad iron comprising a body having 90 a thickened standard at its toe; and a burner tube in the body, the burner tube being provided in its end with an opening discharging against the toe.

2. A sad iron comprising a body having 95 a thickened standard at its toe; and a burner tube in the body, the burner tube having an opening in its end discharging against the toe, the tube being downwardly and forwardly inclined at its forward end to form 100 a deflector for the opening.

3. In a sad iron, a body; a lid for the body; a burner in the body and having an extension; a flame spreader above the burner and provided with an extension co- 105 acting with the extension of the burner to hold the burner in place; and means for connecting the flame spreader with the lid.

4. In a sad iron, a body, a lid for the body and provided with a bracket; a burner 110 tube having an extension abutting against the bracket; a flame spreader above the burner and provided with an extension engaged with the extension of the burner tube and with the bracket; and means for connecting the flame spreader with the lid.

5. In a sad iron, a body; a lid for the body; a burner in the body; a flame spreader disposed in the body and below the lid; a handle disposed above the lid; a shield interposed between the handle and the lid and projecting laterally beyond the handle to act as a guard therefor; and a securing element uniting the handle, the shield, the lid and the flame spreader. 115

6. In a sad iron, a body; a lid for the body; a burner engaged adjacent one end with the lid; a flame spreader above the burner and below the lid, and engaged with the other end of the burner to hold the 120

first specified end in engagement with the lid; and means for securing the flame spreader to the lid.

7. In a sad iron, a body, a lid for the body and provided adjacent its end with a depending wing having a notch; a flame spreader beneath the lid and equipped with a depending projection; a burner tube engaged with the projection and held thereby in the notch; and means for securing the flame spreader to the lid.

8. A sad iron comprising as constituent parts, a body and a lid, one of said constituent parts being provided with a notch 15 terminated in an enlarged seat, the other of said constituent parts being provided with a spindle, mounted to rock in the seat,

the spindle being flattened on one side, whereby the spindle may be disengaged from the notch only when the lid is in a 20 position intermediate a fully opened position and a fully closed position, the spindle coöperating with the seat to form a pivotal mounting for the lid on the body; and a heating means housed within the compartment defined by the lid and the body. 25

In testimony that I claim the foregoing as my own, I have hereto affixed my signature in the presence of two witnesses.

CHARLES C. GRIDLEY.
